UNITED STATES PATENT OFFICE.

WILLIAM L. TUELL AND HERMAN H. BORGERDING, OF NEW ALBANY,
INDIANA.

DRAWER-STOP.

No. 852,247.

Specification of Letters Patent.

Patented April 30, 1907.

Application filed December 18, 1905. Serial No. 292,309.

To all whom it may concern:

Be it known that we, WILLIAM L. TUELL and HERMAN H. BORGERDING, citizens of the United States, residing at New Albany, in the county of Floyd and State of Indiana, have invented certain new and useful Improvements in Drawer-Stops; and we do declare the following to be a full, clear, and exact description of the invention, such as will enable others skilled in the art to which it appertains to make and use the same.

This invention relates to improvements in drawer stops.

The object of the invention is to provide a device of this character by means of which drawers are held in position and prevented from being pushed in too far.

A further object is to provide a device of this character which is simple and inexpensive in construction and which may be quickly and easily applied and which has great strength to resist the strain to which it is subjected.

With the above and other objects in view, the invention consists of certain novel features of construction, combination and arrangement of parts, as will be hereinafter described and claimed.

In the accompanying drawings:—Figure 1 is a sectional view through a portion of a desk and drawer, showing the application of the invention; and Fig. 2 is a perspective view of the stop.

Referring more particularly to the drawings, 1 denotes the stop, which is formed from a wedge-shaped piece of flat metal having the head-portion 2 provided with integral, laterally-projecting wings 3, which are curved slightly inwardly and lie in approximately the same plane as said head 2, the edges of said wedge-shaped piece of metal being cut away to form said wings 3, the

lower edges of said wings being preferably pointed to engage the drawer and hold said wings securely. This curvature of the wings produces a head which is transversely concavo-convex, so that when applied to a drawer offers greater resistance than a straight piece of metal and is not so liable to become bent or broken. Formed integral with the head 2 below the wings 3 is a securing point 4 lying in the same plane as the head and adapted to be driven into the wood of the drawer frame. The point 4 is preferably notched, as at 5, along its edges so that when driven into the wood the point will be securely held against accidental withdrawal.

From the foregoing description, taken in connection with the accompanying drawings, the construction and operation of the invention will be readily understood without requiring a more extended explanation.

Having thus described our invention, what we claim as new and desire to secure by Letters-Patent, is:—

A drawer stop comprising a head having laterally extending, transversely curved wings lying in approximately the same plane as the head, and forming in conjunction therewith a transversely concavo-convex strain-resisting member, said wings having means for penetrating and engaging the article to which the stop is to be applied, and a securing point formed on said head in the same plane therewith and having notches for holding it against withdrawal.

In testimony whereof we have hereunto set our hand in presence of two subscribing witnesses.

WILLIAM L. TUELL.

HERMAN H. BORGERDING.
